UNITED STATES PATENT OFFICE.

FRANK W. THILL, OF CALDWELL, NEW JERSEY, ASSIGNOR TO LEMUEL C. BRISTOW, OF CALDWELL, NEW JERSEY.

AUTOMATIC TRAIN-STOP.

1,291,255.

Specification of Letters Patent. Patented Jan. 14, 1919.

Application filed May 6, 1915. Serial No. 26,378.

To all whom it may concern:

Be it known that I, FRANK W. THILL, a citizen of the United States, residing at Caldwell, in the county of Essex and State 5 of New Jersey, have invented certain new and useful Improvements in Automatic Train-Stops, of which the following is a specification.

This invention relates to an automatic 10 train stop and the principal object of the invention is to provide improved means for venting the train line pipe in case the engineer does not see a danger signal and thus permit the brakes to be applied and bring 15 the train to a stop.

Another object of the invention is to provide an improved type of track device which will be set when the semaphore arm is moved to a danger position and which will 20 be returned to an inoperative position when the semaphore arm is set at safety.

Another object of the invention is to so construct the train device as to permit the brakes to be set regardless of the direction 25 in which the train is moving.

Another object of the invention is to provide an improved type of cylinder valve for the system, the valve being so constructed as to permit air from the train line to return the valve to its normal position after 30 the brakes have been set.

Another object of the invention is to so construct this device as to permit it to be used either in connection with a track device positioned adjacent the rails or with a 35 device suspended from an overhead bridge.

Another object of the invention is to so construct this device as to permit the train to be operated from a temporary trip connected with one of the rails.

This invention is illustrated in the accompanying drawings, wherein:—

Figure 1 is a view showing the system applied to a train with a semaphore arm set 45 at danger to operate the device.

Fig. 2 is a fragmentary view of the air-brake system showing the improved device connected therewith, one of the piston valves being shown in section and the other 60 in elevation.

Fig. 3 is a perspective view of the track device.

Fig. 4 is a fragmentary view of the connection between the semaphore arm and the track device. 55

Fig. 5 is a view in elevation showing the manner of mounting a trip upon an overhead bridge.

Fig. 6 is a perspective view of a trip which can be temporarily connected with a 60 rail.

The track device or trip shown in Fig. 3 will be secured to the block 10 positioned between the ties 11 by means of the bearing 12 in which the rocker shaft 13 is rotatably mounted. This rocker shaft carries the trip or shoe 14 which will be positioned between the rails 15 when in an operative position as shown in Fig. 1 and also carries an arm 16 with which the rod 17 is connected. This rod 17 has its opposite end connected with the bell crank lever 18 which bell crank lever is connected with the rod 19 as shown in Fig. 4. The rod 19 extends through the bell crank 20 mounted upon the semaphore 70 poles 21 and connected with the lower end of the rod 22 leading to the semaphore arm 23. Therefore when the semaphore arm 23 is moved the shaft 13 will be rocked and the shoe swung either to a set position or 75 to an inoperative position according to the position of the semaphore arm. 80

In Figs. 5 and 6 there has been shown a modified form of trip mechanism. The form shown in Fig. 5 is provided so that 85 the trip can be connected with a signal bridge 24 with the bearing 12 secured to the bridge and the rocker shaft 13 positioned beneath the same. In this form the arm 16 will be connected with the bell crank lever 90 25 by means of a rod 26 and the bell crank lever 25 will be connected with the bell crank lever 27 by means of a rod 28. The semaphore arm 29 which is mounted upon the pole 30 is connected with the bell crank lever 27 by means of a rod 31 and therefore when the semaphore arm is moved the rocker shaft 13 will be rotated and the trip 100 14 moved either to a set or an inoperative position according to the position of the semaphore arm. The device shown in Fig. 6 is simply a temporary device and comprises the shoe or trip 32 which is carried by the arm 33 leading from the clamp 34.

This clamp 34 will be releasably connected with the rail 15 by means of the leaf 35 and set screws 36 and will be put in place by the flagman or conductor of a train in case 5 a train stops unexpectedly or for any other reason it is desired to stop a train between the usual signal stations.

The train device is disclosed in Figs. 1 and 2, and in these figures the train line is 10 indicated by the numeral 37 and the auxiliary tank by the numeral 38. This auxiliary tank 38 receives its supply of air from the train line 37 through the medium of the pipes 39, 40, and 41, the pipes 39 and 41 leading respectively to the cylinders 42 and 15 43 and pipe 40 connecting the cylinders. The pipe 39 communicates with the auxiliary reservoir 38 through the medium of the pipe 44 which pipe 44 communicates 20 with the lower end of the cylinder 42 and is provided with a branch 45 communicating with the lower end of the cylinder 43. The pipe 41 not only communicates with the upper end portion of the cylinder 43 but is 25 provided with a branch 46 having its extension 47 communicating with the intermediate portion of the cylinder 43. Each of these cylinders is also provided with outlets 48 and 49 and with a passageway 50 30 of small capacity leading from the inner end portion of the openings with which the pipes 40 and 41 communicate and opening within the chamber 51.

From an inspection of Fig. 2 with particular reference to cylinder 43 it will be 35 seen that each of these cylinders is provided with the chambers 51 and 52 connected by the neck 53. The pistons 54 and 55 which are slidably mounted in these chambers are 40 connected by the shaft 56 carrying the valve 57 in which there is provided the U-shaped passageway 58. A spring 59 is provided to engage the wall of the cylinder thus holding the valve 57 in tight engagement with the 45 cylinder wall and preventing leakage of air through the passageway 58 when the valve is in the position shown. Actuating rods 60 extend from the piston 55 through the head 61 of the cylinders and are provided with 50 rollers 62 engaging the arms 63 and 64 of the rocker lever or trigger 65. This lever or trigger 65 will be pivotally mounted upon the cab of the engine at any convenient point by means of a suitable pin passing 55 through the opening 66. Therefore the lever or trigger will extend as shown in Fig. 1 so that the roller 67 can engage the trip shoe and swing upon its pivot to move one of the actuating rods 60 inwardly.

60 This apparatus will be preferably mounted as shown in Fig. 1 with the trigger or lever 65 extending downwardly to engage the trip shoe in case the engineer does not see the semaphore arm or signal of the track 65 walker or conductor of the preceding train.

As the lever 65 is rocked by the trip the arm 63 or 64 will be moved to raise the actuating rod 60 of the cylinder 42 or 43. For convenience sake it will be assumed that the rod 60 of the cylinder 43 will be actuated 70 As this rod moves upwardly it raises the pistons 54 and 55 and uncovers the opening communicating with the pipe 45 and covers the opening 48. At the same time the opening communicating with the pipe 40 will be 75 closed and the opening communicating with the pipe 41 will also be closed with the exception of the small passageway 50. As these pistons move upwardly the sliding block valves 57 will move upwardly so that 80 the ends of the U-shaped passage 58 will register with the opening communicating with the extension 47 and with the branch 68 of the outlet 49. These pistons and the shaft 56 carrying the same will be moved upwardly 85 until the opening 48 is uncovered and permits the air in the auxiliary reservoir 38 to exhaust through the pipes 44 and 45 into the chamber 52 and out through the opening 48. The air in the train line 37 will exhaust through 90 the pipes 41 and 46 and extension 47 and thus the brakes upon all of the cars of the train as well as upon the engine will be applied. In order to prevent the air from exhausting in the train line too rapidly there is provided 95 the usual automatic reducing valve 69 which valve controls the passage of air through the pipe 41 and causes a service application of the brakes to be applied instead of an emergency application. Therefore the train will 100 be brought to a stop if it passes a signal and danger of collision will be avoided. It should also be noted that this lever 65 is so positioned that if the engine should jump the track the lever will strike the ties or rails 105 and thus be moved to an operative position to apply the brakes.

After the train has been brought to a stop it is desired to release the brakes and in order to do so the auxiliary tank must be 110 again filled with air from the train line. This is accomplished by means of the air which will pass through the small passageway 50 into the upper portion of the chamber 51. The principal portion of the air 115 passing through the pipe 41 will pass through the pipe 46 but a certain amount will pass through the passageway 50 into the chamber 51 and the upper portion of this chamber will be gradually filled with air 120 under pressure thus moving the piston downwardly. This piston will at first move slowly until the passageway 58 is out of alignment with the passageways in the walls of the cylinders and the passage of air 125 through the extension 47 will then be cut off and the air will then pass more rapidly into the chamber 51 and force the cylinder downwardly. It should be noted that the opening communicating with the pipe 40 will not 130

be uncovered until the piston 54 is almost entirely in the position shown in Fig. 2 and therefore the air in the compartment 52 will not be under pressure and will offer no resistance to the movement of the piston 55. As soon as the piston is in the original position the air will pass through the pipe 40 into the chamber 51 of the cylinder 42 and through the pipe 39 into the auxiliary reservoir tank 38. The dial 70 in the cab will indicate when the air in the auxiliary reservoir is under sufficient pressure and the engineer will therefore know when he can release the brakes.

15 I have therefore provided a train stopping apparatus which is so constructed that the train can be brought to a stop if it passes a signal or if the wheels jump the track, the apparatus being so constructed that after 20 the train has been brought to a stop the brakes may be released. It should also be noted that this mechanism is so constructed that it may be applied to air brake systems now in use.

25 What is claimed is:—

1. In an air brake system a train line, an auxiliary tank, a cylinder provided with end chambers and with a neck connecting said chambers, pistons slidably mounted in said chambers, a shaft connecting said pistons and extending through said neck, an actuating rod extending from one of said pistons out of said cylinder, said cylinder being provided with an outlet and an inlet 30 passage communicating with the lower chamber, a pipe leading from said auxiliary reservoir and communicating with said inlet passageway, a pipe leading from the train line and communicating with the upper chamber, a pipe communicating with the upper chamber and with the pipe leading from said auxiliary reservoir, said cylinder being provided with an inlet opening and an outlet opening communicating with said 35 neck, a block valve mounted upon said shaft intermediate said pistons and provided with a passageway for bridging the space between the inlet and outlet openings of said neck, and a pipe leading from the inlet opening of said neck and communicating with the pipe leading from said train line.

40 2. In an air brake system a train line, an auxiliary reservoir, a cylinder, a pipe leading from said auxiliary reservoir and communicating with the lower end portion of said cylinder, a pipe leading from said last mentioned pipe and communicating with the upper end portion of said cylinder, a pipe leading from the upper end portion of said cylinder and communicating with said train line pipe, a pipe leading from said last mentioned pipe and communicating with the intermediate portion of said cylinder, a piston slidably mounted in each end portion of said cylinder, a shaft connecting said

pistons, an actuating rod leading from one of said piston through said cylinder, said cylinder being provided with an outlet adjacent its lower end and with an outlet intermediate its length, and a sliding block 70 valve carried by said shaft and provided with a passageway having its ends positioned to register with said last mentioned outlet and with said last mentioned pipe when said pistons are moved out of their 75 normal positions.

3. In an air brake operating system a train line, an auxiliary reservoir, cylinders positioned beneath said train line and auxiliary reservoir and having a piston movably 80 mounted therein, pipes leading from said pneumatically operated means to said auxiliary reservoir and train line pipe, and mechanically operated means for starting said piston from its normal position to a set position, the air from said auxiliary reservoir completing the movement of the piston toward a set position and the air from said train line pipe returning the piston to its 85 normal position.

4. An air brake system including a train line pipe, an auxiliary reservoir, a valve cylinder communicating with said auxiliary reservoir and with said train line pipe, a reducing valve positioned between said valve 90 cylinder and said train line pipe, valve means carried by said pneumatically operated means, and actuating means for giving the valve of said valve cylinder its initial movement in one direction.

5. An air brake system including a train line pipe, an auxiliary reservoir, valve means communicating with said auxiliary reservoir and with said train line pipe, a reducing valve positioned between said valve means 95 and said train line pipe, and means for giving said valve means its initial movement in one direction.

6. An air brake system including a train line pipe, an auxiliary reservoir, valve means positioned between said train line pipe and auxiliary reservoir and including slidably mounted plungers having actuating rods, and actuating means for moving said plungers in one direction.

7. An air brake operating system embodying therein an auxiliary reservoir, a cylinder, pipe connections whereby air from a train line may be delivered through one portion of said cylinder to said reservoir, pipes 110 whereby air may be delivered from said reservoir to another portion of said cylinder, means adapted to substantially simultaneously control the flow of air to and from said reservoir, means acting in synchronism 115 with said last named means whereby when the flow of air to said reservoir is interrupted, a train line may be vented, and actuating means adapted to engage a contact actuated by a danger signal, whereby said 120 125 130

means controlling the flow of air to and from said reservoir and the venting of the train line will be automatically actuated.

8. An air brake operating system embodying therein an auxiliary reservoir, a cylinder having chambers at the opposite ends thereof, each of said chambers having an inlet and an outlet port therein, and said cylinder having therein an inlet and an outlet port intermediate said chambers, pipes connecting the outlet port of one of said chambers and the inlet port of said other chamber with the reservoir, a pipe connecting the inlet port intermediate said chambers and the inlet port of one of said chambers with a train line, connecting pistons

20 mounted in said chambers respectively controlling the ports in said chambers, a valve mechanism operating in synchronism with said pistons in controlling said ports intermediate said chambers, and actuating means adapted to engage a contact actuated by a danger signal, whereby said means controlling the flow of air to and from said reservoir and the venting of the train line will 25 be automatically actuated.

In testimony whereof I affix my signature in presence of two witnesses.

FRANK W. THILL.
